CASING FOR AN INK MARKER

Joseph E. Corr, Jr., Riverside, Conn., assignor to Eagle Pencil Company, Danbury, Conn., a corporation of Delaware

Filed Oct. 7, 1966, Ser. No. 4,188

Term of patent 14 years

(Cl. D74—17)

FIG. 1

FIG. 2

FIG. 4

FIGS. 1 and 2 are side elevational views of a casing for an ink marker showing my new design taken from two different positions;

FIG. 3 is a top plan view of the casing for an ink marker, and

FIG. 4 is a bottom plan view thereof.

The dominant feature of my invention resides in an elongated barrel having a cylindrical portion terminating in a cylindrical band at one end and continuing with a tapered tip having a curved surface extending from said band and terminating in a reduced diameter truncated conical protuberance having an angled end face, and a tapered fluted cap having a curved surface secured at the other end of the barrel and of dimensions substantially the same as the tapered tip.

I claim:

The ornamental design for a casing for an ink marker, substantially as shown and described.
